United States Patent

Des. 234,698
Patented Apr. 1, 1975

234,698

MAGNETIC STRIPE CARD READER OR THE LIKE

Ronald I. Conway, Port Ewen, Robert V. Jones, Kingston,
John J. Natoli, Woodstock, and John V. Stram, Pough-
keepsie, N.Y., assignors to International Business
Machines Corporation, Armonk, N.Y.

Filed July 16, 1973, Ser. No. 379,877

Term of patent 14 years

Int. Cl. D14—02

U.S. Cl. D26—5 C

FIG. 1

FIG. 2

FIG. 1 is a front, right side and top perspective view of a magnetic stripe card reader or the like, showing our design.

FIG. 2 is a rear, left side and top perspective view of the design of FIG. 1.

The bottom surface of the design is plain.

We claim:

The ornamental design for a magnetic stripe card reader or the like, substantially as shown and described.
